AIRCRAFT GUN TURRET

George Bussiere and Edward C. Holton, Los Angeles, Calif., assignors to North American Aviation, Inc.

Application February 20, 1945, Serial No. 578,892

15 Claims. (Cl. 89—37.5)

1

The present invention relates to armament and ordnance and more particularly to gun turrets of the power-driven type adapted for use in aircraft and the like.

The present invention comprises essentially a columnar support carrying multiple guns faired within individual turrets at each of the terminals of the columns. The invention embraces a novel method of supporting the columns and turrets from the fuselage structure in the waist gun position as well as the manner of supporting the ammunition boxes of relatively great capacity from the columnar support. The invention also includes improvements in the operating mechanism for rotating the individual turrets both in azimuth and elevation and in the driving mechanism by which this is accomplished. Other features of the present invention relate to the novel arrangement and organization of the respective elements of the turret structure which results in a highly efficient and rugged assembly of great strength-to-weight ratio for both individual and multiple turret mounts.

It is accordingly a major object of the present invention to provide a columnar support gun turret which is particularly adapted for use in the waist position of the aircraft fuselage. It is a further object to provide a power-driven dual turret arrangement in which each of the turrets carries multiple machine guns capable of individual or simultaneous aiming and firing. A further object resides in the provision of a remote controlled turret which offers relatively little resistance to forward flight in its stowed position. A further object of this invention comprises the provision of an improved structural support system for a columnar type turret whereby the turret is rigidly supported and transmits firing recoil to the fuselage structure while providing adequate clearance around the support for access and operation by the gunners. Other objects and advantages reside in the specific relationship and organization of the elements comprising the present gun turret installation and will become apparent after a reading of the present specification and the accompanying drawings, forming a part hereof, in which:

Fig. 1 is a transverse elevation looking aft toward the waist position of an aircraft fuselage provided with the aircraft gun turret of the present invention;

Fig. 2 is an elevation taken along the lines 2—2 of Fig. 1;

Fig. 3 is an enlarged sectional elevation of the

2

upper half of the turret shown in Fig. 2 as taken along the lines 3—3 of Fig. 4;

Fig. 4 is an enlarged cross-sectional elevation of the upper turret assembly of Fig. 3 as taken along the lines 4—4 thereof;

Fig. 5 is a detailed cross-sectional view of the upper columnar support or pedestal;

Fig. 6 is a transverse sectional view of the cap portion of the support as taken along the lines 6—6 of Fig. 5;

Fig. 7 is a horizontal plan view looking upwardly of the drive portion of the base section of the column as taken along the lines 7—7 of Fig. 5;

Fig. 8 is a part-sectional elevational view of the base portion of the upper columnar support shown in Fig. 5;

Fig. 9 is a plan view of the structural support arrangement for the turrets;

Fig. 10 is an enlarged plan view of the structural support arrangement shown in Fig. 9;

Fig. 11 is a partial side elevational view of the same; and

Fig. 12 is a detail sectional view of the rear mounting for one of the guns.

Referring now to Figs. 1 and 2, the numeral 10 indicates the waist portion of an aircraft fuselage of substantially cylindrical section provided with transverse bulkhead frames 11 and 12. The upper or deck portion of the fuselage is provided with a circular opening 13 around which there is formed a part-spherical fairing portion 14 within which the upper turret 16 is adapted to be rotated with the intermediate gap sealed by the extruded rubber tube 15. The transverse horizontal axis of the fuselage at the turret installation is indicated by the line A—B and the longitudinal axis of the fuselage and turret installation is indicated by the axis C—D which intersects A—B at the center O. The vertical axis of the turret installation is indicated by the line E—F and disposed on this vertical axis at the bottom or belly portion of the fuselage there is provided a similar circular opening 17 around which is also built a part-spherical fairing portion 18 within which the lower turret 20 is adapted to be operated in a sealed relationship by means of the intermediate rubber seal tube 19.

The inner chord angles 11a and 12a of the bulkhead frames 11 and 12 are vertically disposed for a substantial distance above and below the axis A—B and are located a sufficient distance from the outside of the mid-portion of the bulkhead frame to give it relatively great

depth at its mid-portion. To these portions of the bulkhead frames 11 and 12, there are extended from the right side of the fuselage looking forward, or from the top or outer side of Fig. 10, the bracket structures 21 and 22 which extend from the outer wall of the fuselage to a point just beyond its center O on the axis C—D. Across the outer ends of the brackets 21 and 22 there are provided a pair of longitudinal beams 23 and 24 symmetrically disposed about the vertical axis E—F on each side of the central point O and rigidly framed and attached to the transverse brackets and the vertical angles 11c, 11d, 12c and 12d fastened to the vertical web plates 11b and 12b, respectively. The structure comprising the bulkheads 11 and 12, the brackets 21 and 22, and the beams 23 and 24, and certain stiffening members to be described in connection with Figs. 9, 10 and 11, comprise the support for the upper and lower turrets 16 and 20.

On the inside of the fuselage adjacent the lower opening 17 there are provided channel or sill members 26 and 27, representing, respectively, the longitudinal and transverse floor framing channels, bent to follow the circular outline of the opening 17 and the adjacent fairing 18, having their upper flanges in the same horizontal plane to support the floor plates 25. These channel members are of varying depths to follow the contour of the intersection of the opening and the cylindrical shape of the fuselage.

The upper turret assembly is supported upon the upper column comprising the pedestal base or bearing portion 28 the azimuth torque shaft portion 29 and the pedestal cap portion 30. A gun limber or support 31 together with the yoke 41, is pivotally mounted for elevational movement upon the pivotal support 32 carried by the pedestal, the limber supporting at each side the dual or twin machine guns 33 and 34. The base portion 28 is provided with a plurality of apertured lug portions 35 adapted to receive the studs 36 carried by the reinforced bracket structure 37 and 38, and to be securely fastened thereto by the nuts 39. It will be noted that the two longitudinal beams 23 and 24, and the short transverse reinforcing members 37 and 38 framed between the longitudinal beams, form a box section or structure 40 of rectangular plan form and into the four corners of which the legs 35 of the pedestal base 28 are attached.

Both the guns 33 and 34, and the upper turret cover or shield 16, are supported from the aforementioned pivot 32 by means of the yoke 41. The gun limber 31 is provided with a socket portion which is adapted to receive the pin 42 of the yoke, the upper flanged portion of which is attached to the limber by means of the screws 43. The pivot member 32 is of tubular construction and is fixedly attached to both the yoke 41 and the gear segment 44 (see Figs. 5 and 6) in order that as the gear segment is rotated in elevation the attached assembly (comprising the pin 32, the yoke 41, the limber 31 and the attached machine guns and turret 16), is moved as a unit.

The front mounting unit 45 for the gun 33, as shown in Figs. 3 and 4, is attached to the threaded aperture 46 in the cross frame portion 47 of the limber 31. The rear mounting unit 48 for the same gun is carried by a bracket 49 supported from the yoke by the bolts 50. The forward mounting 45 is capable of adjustment in elevation and the rear mounting is adjustable in azimuth in order that the guns may be adjusted into the desired aimed settings either with respect to each other, or with respect to the adjacent turret

shield 16. Each of the machine guns is in turn attached to the respective mountings 45 and 48 through connections to the gun trunnions 51 and 52 respectively.

Reference to Figs. 1 to 4 inclusive will reveal that the enclosure for the upper turret 16 is part-spherical in shape with its upper portion, when in the stowed position as shown in these figures, of a relatively flattened intermediate shape with peripheral portions of relatively shorter radius connecting the part-spherical portion. Approximately one half of the spherical portion of the turret 16 has been cut away as defined by the edges 53 and 54 leaving the remaining part-spherical portion 55. The relatively flat outer portion referred to above is indicated at 56 and the more sharply rounded edge portions are indicated at 57. The turret is reinforced by the hat-shaped channel stiffener 58 centrally disposed with respect to the axis E—F and the plane of symmetry of the turret. Brackets 59 and 60 of H cross-section are attached to the channel 58, and by the bolts 61 and 62 are in turn fastened to the limber 31. The turret 16 is preferably provided with a pair of removable panels 16a, in Figs. 1 and 4, in its outer skin or covering in the flattened portion adjacent each side of the channel 58 in order to provide access for servicing and repairing as well as the removal of the machine guns and the associated structure.

Both the upper and lower turrets are of the remotely controlled type, being aimed by means of suitable periscopic sighting arrangements and consequently they do not require transparent portions directly within the turret canopies. The part-spherical portion 55 of the turret cover is attached to the cross-frame portion 47 of the limber 31 by the stiffening framework 63 and the end framing clips 64 and bolts 65. It will accordingly be noted from the shape of the turret cover that in the retracted position shown its projection beyond the outline of the fuselage is relatively small and the resistance to flight is accordingly minimized; and also that in this position the turret is sealed for protection from the weather by the tubular element 15.

The torque shaft portion 29 of the supporting pedestal has fixedly attached to it a pair of projecting brackets 66 and 67 to which a further pair of projection brackets 68 and 69 are attached for the support of the ammunition boxes or containers 70 and 71. In the arrangement which has been illustrated relatively large ammunition boxes 70 and 71 are provided which contain some 600 rounds for each machine gun. It will be noted that these ammunition boxes are fixedly attached to the rotatable portion of the turret structure and they accordingly rotate with the turret and the guns which they feed. The cartridge clips are ejected laterally from each gun toward each other and are ejected down the chutes 74, 75, 72 and 73 into the receiving box 76. (See Figs. 1 and 4.)

Referring now to Fig. 5, and the supporting detail Figures 6 to 8 inclusive, there is shown the column or pedestal support for the upper turret 16 in a detailed cross-sectional elevation. The lower or base portion 28 is provided with two parallel and horizontal driving worms 77 and 78 for the elevation and azimuth control, respectively, of the turret and its guns. As shown in Fig. 7, the worm 77 is mounted upon a shaft 79 which is journaled at 80 and 81, and is provided with a driving connection at 82 for attachment to an external power source to be subsequently

described. The worm 77 drivingly meshes with the worm gear 83 which is attached by the studs 84 to the hollow quill shaft 85. The worm 78 is similarly attached to a short shaft 86 which is journalled at 87 and 88 within the casing of the support member 28, and the shaft 86 is similarly recessed at 89 for attachment to a suitable drive coupling. The worm 78 is in driving engagement with the worm gear 90 which in turn is fixedly attached to the torque pedestal portion 29 by means of the studs 91. Access plates or covers 92 and 93 are provided within the casing of the base portion 28 adjacent the worms 77 and 78, respectively, and a cover plate 94 is releasably attached for access to the bottom portion of the base member, being fastened thereto by the bolts 95.

Bearings 96 and 97, are provided between the upper portion of the base member 28 and the intermediate portion of the torque shaft 29, and between the lower portion of each of these members, respectively, thereby permitting the torque tube 29 to rotate with respect to the fixed base member 28, within which it is journalled. The pedestal head or cap portion 30 is fixedly attached by means of the bolts 98 through the abutting flanged portions 99 and 100 such that rotation of the worm 78 imparts corresponding rotation to the worm gear 90, the torque shaft 29, the cap 30 and the guns and turret 16.

Suitable fire control mechanism, preferably of the electrical type, is provided from a remote station by suitable slip-ring and brush mechanism from the fixed base pedestal 28 to the movable torque portion 29, and thence to the guns of the upper turret as indicated by the dotted lines 101 in Figs. 2 and 3. As indicated in Fig. 8, the fire control wiring is brought in from the gunner's position to the contacts 102 within the box 103 to the brushes 104 for engagement with the slip-rings 105 which are fixedly attached to the rotatable torque member 29. Each of the rings 105 on the torque member 29 is connected by the wiring 106, suitably clamped as at 107 to the inside wall of the torque pedestal member 29, through the outlet fitting 108 to a support connection 109 on the inside of the turret, and thence to the firing control mechanism 110 on the guns 33 and 34. Suitable means for grounding stray currents which may accumulate or be transmitted to the movable parts of the gun turret structure are picked up from the slip-ring 111 by means of the brush connections 112 which are threaded directly into and grounded within the base pedestal member 28. It will be understood that the base member 28 itself is grounded to the aircraft structure either by virtue of its supporting contact thereby or by separate bonding or grounding connections.

As shown in Fig. 5, the inner quill shaft 85 is journalled within the torque member 29 by means of the lower anti-friction bearing 113, and the upper bearing 114, these bearings being retained by the spanner nuts 115 and 116, respectively. A bevel gear 117 is attached, as by the nuts 118, to the upper thickened terminal of the quill shaft 85, being locked in its adjusted position by the screw 119. Between the bevel gear 117 and the previously referred to worm gear segment 44 on the pivot 32, there is disposed an angularly inclined shaft 120 journalled at its higher end in the ball bearing 121 and at its lower end in the roller bearing 122. A worm 123 is formed upon or fixedly attached to the shaft 120 being held thereby in meshing engagement with gear seg-

ment 44. The lower end of the shaft 120 has fixed thereto the bevel gear 124, which is retained by the lock nut 125, and meshes with gear 117. Access openings are provided in the walls 5 of the cap member 30 adjacent the ends of the shaft 120, being provided with covers 126 and 127 respectively.

The pivot 32, which permits the yoke 41 to be rotationally elevated about its axis, is of the tubular type being retained within the hub 41a of the yoke by the cup-shaped end retainers 32a and the through bolt 32b. The yoke 41 is preferably constructed in two halves, attached together by the bolts 41e through the lower part of the pin fitting 42 such that the serrated end 41b of the hubs 41a can engage the similarly serrated or toothed surfaces 44a on the gear segment 44. The engagement of these serrated surfaces insures positive rotation of the yoke and its attached guns and turret as the gear segment 44 is caused to rotate by rotation of the shaft 79, the worm and worm-wheel set 77 and 83, quill shaft 85 and the bevel gear set 117 and 124. The cap or head portion 30 of the pedestal mount is provided with a pair of anti-friction bearings 128 within which the tubular pin and hub assembly 32 is adapted to rotate and the upper portion of the cap 30 is provided with a cover plate 41c held by the bolts 41d providing for ready access to the interior of the pedestal cap.

At the base of the pedestal member 28, an hydraulic gun charger line 129 is connected to the swing joint fitting 130, the upper half of which is attached at 130a to the quill shaft 85 and the centrally disposed conduit 131. Similarly the lower portion of the swing or swivel joint 132 is attached by the bolts 132a through the bevel gear 117 to the upper terminal of the quill shaft 85 and in communication with the central conduit 131, which is accordingly adapted to rotate with the quill shaft. The upper portion of the swing joint 132 is fluidly connected to the bushed fitting 133 and by means of similar swing joints, or the use of flexible hose, is connected to the swing joint 134 supported upon the cap portion of the pedestal and thence through the flexible hose 135 and the junction box fitting 136, attached to the re-enforcing channel 58, to the gun charger attachment adjacent each gun.

As indicated in Fig. 1, each turret and its guns are driven by power units 137 of the electrically driven hydraulic pump type or other suitable and available power mechanism. The speed and direction of movement of the turrets are automatically determined by the sighting mechanism, which may be remote from the turrets. In other words the gun sight is aimed at the target and the turret automatically follows, continuing to track the target as the sight is moved, and coming to rest upon the discontinuance of movement of the sight by virtue of the inclusion of a follow-up arrangement in the turret power mechanism. The power for operating it in azimuth and tilting it in elevational adjustment, is provided by the electrically driven hydraulic pumps 137a, which in turn drive hydraulic motors. An electrically controlled valving arrangement is interposed between the pump and hydraulic motor, being hooked in with the sighting and fire control mechanism which is electrically controlled to vary the output of the pump whereby the speed of the hydraulic motor is also varied. Each electric motor driven hydraulic pump 137a is of the constant speed type and runs continuously while

the power is "on" whether the turret is in motion or not.

The installation includes a differential compensator mechanism 138 which may be compared to the differential in the rear end of an automobile. As shown in Fig. 5 the turret design includes two co-axial or concentric transmission shafts 85 and 29 within the pedestal column 28. The first torque shaft 85 operates a worm gear mechanism 123 at the top of the pedestal to effect the desired elevational adjustment of the guns. The other shaft 29 is driven by the worm gear set 78-90 in the turret base whereby the entire turret and canopy is rotated. When the turret is moved in both planes simultaneously it becomes necessary to compensate for the component of movement which is introduced in each of the gear trains by virtue of the relative movement of the other train. In a case where the turret is slowly elevating while rotating clockwise, for example, the fire control mechanism would require a compensation to "add in" some additional elevational movement. Conversely, with the turret slowly elevating while rotating counter-clockwise, it would be necessary to "subtract" a certain amount of elevational movement. The aforementioned units are connected by the drive shafts 139 and universal joints 140 to the respective worm drive shaft connections 82 and 89, in the base of the turret pedestal.

With the exception of the details of the limber of the lower pair of guns, the lower pedestal and turret assembly is substantially identical with the upper assembly which has been described above. The pedestal base or attachment section 141 is suspended from the central box portion 40 and within this base portion there is rotatably journaled the torque portion 142, and the terminal or end portion 143, corresponding to the upper cap portion 30. A substantially similar yoke 144 is suspended from the pivots in the end portion 143 and has suspended therefrom the limber 145 of the guns 146 and 147. Front and rear adjusting mounts 148 and 149 are provided between the gun and the limber 145 to permit aligning and setting of the guns with respect to the turret and the aircraft structure. A similar fire control cable 150 extends from the torque section of the lower pedestal 142 to the firing controls for the guns and a flexible hydraulic hose 151 extends from the lower support member 143 through the junction fitting 152 to the gun chargers of the respective guns. Each of the lower guns 146 and 147 is provided with individual ammunition boxes 153 respectively carried upon the brackets 154 supported from the intermediate portion 142 of the lower suspension structure.

In Fig. 9 there is diagrammatically shown to a reduced scale a plan of the structural support for the upper and lower columns. A more detailed plan view to a larger scale is shown in Fig. 10 and a side elevational view of the structural support of Fig. 10 is shown in Fig. 11. Diagonal braces 155 and 156 extend horizontally from the junction of the former frames 11 and 12 with the transverse brackets 21 and 22. These diagonals are attached at their outer ends to the longitudinal beam 23 adjacent the ends of the box section 40. Intermediate fuselage former rings are provided at 157 and 158 and horizontal struts 159 and 160 extend in a longitudinal direction between the diagonal braces 155 and 156. These struts serve both to stiffen the braces and to provide the support for the aforementioned turret drive mechanism 137-138. A plurality of

interconnecting angle ties 24a are attached across the longitudinal beams 23 and 24, extending transversely or parallel to the former frames 11 and 12, as shown in Figs. 10 and 11. The outer terminals of the diagonals 155 and 156 are attached and braced to the former frames and side wall structure by means of gusset plates 155a and 156a. These diagonals are also attached to the longitudinal beams 23 by means of the gussets 155b and 156b respectively, both of which are of channel cross-section. The intermediate portions of the diagonals 155 and 156 are each tied to the transverse framing by means of the horizontal plates 11e and 12e which are in turn attached to the transverse frames by means of the horizontal angles 11f and 12f, respectively.

The above mentioned rear mounting unit 48 is shown in detail in Fig. 12. The rear portion of the gun 33 is provided with a pair of apertured downwardly extending lugs 33a within which the gun trunnion 52 is adapted to be journaled. The rear adjusting mount 48 is provided with a quick disconnect fitting 48a and has a V-edge attachment portion 48b. As indicated above the rear portion of the gun is supported from the yoke 41 by a bracket 49 having complementary V-grooves 49a within which the unit 48 may slide to permit of a slight recoil movement. The outer cover of the unit 48a has a knurled rim and contains on its inner surface a pair of arcuate slots arranged in opposed relationship. The post portion carried by the supporting part 48b is provided with a complementary annular groove adjacent to its upper end and a pair of ball bearings 48d are arranged for cooperative engagement between the cam slots of the inner surface of the cover 48a and the annular groove in the post portion 48b.

The unit 48 provides an arrangement whereby a quarter turn of the knurled cap 48a disengages the balls 48d and allows the gun 33 to be lifted from the mount 48. The upper surface of the knurled cap 48a is apertured to permit the extension therethrough of the internally threaded lug or eye 48c which is restrained from upward movement by a retaining flange engaged by the knurled cap. The boss 48c is provided with a transversely threaded bore to receive the adjusting sleeve 48e which in turn is keyed to the shank of the adjusting trunnion bolt 52. It will accordingly be noted that as the nut 52a is loosened and the bolt 52 rotated, the lug 48c will advance or retreat with respect to the threaded sleeve 48e, imparting similar movement in a horizontal plane to the gun 33, which may be locked in that position by tightening the nut 52a.

For purposes of explaining the present invention, the turrets have been indicated in the drawings as having spherical portions of approximately 36 inches in diameter, housing twin machine guns of .50 calibre, with individual ammunition boxes of approximately 600 rounds capacity. It will, of course, be understood that the present invention is applicable to turrets of other sizes, as well as guns and ammunition containers of various sizes and capacities. The drive units for the lower turret are substantially the same as those which have been described above for the upper turret. The two turrets may be operated either simultaneously in unison or, on the other hand, they may be separately and individually operated for training upon separate targets. In Fig. 2, there has been indicated in dotted lines the fully depressed position of the lower guns 146 and 147 in which they

have been rotated 90 degrees about the lower yoke pivot from their full line position. It will, of course, be understood that in this position of the lower turret, the upper guns will be ineffective for purposes of firing upon the same objective. The fields of fire of each turret overlap slightly and suitable automatic limiting devices are preferably provided in the fire control systems of each turret to prevent their firing at times when portions of the airplane become aligned with the line of fire of the guns. As indicated above the empty cases and belt links projected from the upper pair of guns are guided by the chutes 14 and 15 into the receiving hopper 16, and the cases and links of the lower guns are similarly salvaged by suitable conveyor means, or they may be ejected through the bottom of the turret clear of the airplane.

Other forms and modifications of the present invention, both with respect to its general arrangement and the details of its several parts, which may become apparent to those skilled in the art after reading the present description, are all intended to come within the scope and spirit of this invention as more particularly set forth in the appended claims.

We claim:

1. A support for a dual aircraft turret installation comprising a fuselage structure having upwardly and downwardly directed openings therein, upper and lower turrets disposed within said respective openings, said fuselage structure including a pair of transverse former rings disposed on each side of said fuselage openings, laterally extending beams supported from one side only of each of said fuselage rings, longitudinal beams having their ends framed to the ends of said laterally extending beams and columnar type support means attached to the upper and lower sides of said longitudinal beams for the movable support of said upper and lower turrets disposed within said upper and lower fuselage openings whereby the opposite side of said fuselage is unobstructed to permit fore and aft access therethrough.

2. A column support for an aircraft gun turret comprising a tubular fixed base portion supported by the aircraft, a hollow co-axial column portion rotatably journaled within said base portion, a rotatable cap portion fixedly attached to said rotatable portion for rotation therewith upon a common axis, pivot means carried by said cap portion for rotation about an axis normal to the axis of said rotatable column support portions, a gun turret pivotally mounted upon said cap pivot means for rotation therewith and with respect thereto, power drive means extending through said fixed base portion adapted for the rotation of said rotatable column support portions and said gun turret about said common axis of rotation and drive transmission means extending from said fixed base portion co-axially through and housed within said rotatable portions constructed and arranged to rotate said pivot means and said gun turret about said second axis normal to said common axis.

3. In an aircraft gun turret installation, a pedestal for the adjustable support of a gun turret from the aircraft structure, said pedestal including a base portion fixed to the aircraft structure and a tubular rotatable portion journaled within said base portion for rotation on a vertical axis, said tubular rotatable portion having a pivot journaled therein for rotation

upon a transverse axis normal to the axis of rotation of said tubular portion, yoke means fixed to said pivot arranged to rotate therewith about said transverse pivot axis, a gun turret carried by said yoke means, dual power sources for the rotation of said gun turret about each of said axes of rotation, first gear means operatively interconnecting a first of said power sources with said tubular portion for rotation of said gun turret about the first said axis, shaft means co-axially disposed and journaled within said tubular portion, second gear means operatively interconnecting said second power source and a first end of said shaft means for rotation thereof about said vertical axis, further gear means operatively interconnecting the opposite end of said shaft means with said yoke means for the rotation of said yoke means about said transverse axis and the concurrent elevational rotation of said gun turret.

4. A gun turret installation for a waist position in an aircraft fuselage having vertically aligned openings in its upper and lower portions; said fuselage including a framework comprising a pair of transverse former rings disposed fore and aft of said vertically aligned openings; structural support means including elements laterally extending from the said framework and said former rings from one side of said fuselage only, longitudinally extending members interconnecting the free ends of said laterally extending support means, and stiffening elements extending between said former rings and said longitudinally extending beam elements; a gun turret arranged for controlled movements within each of said fuselage openings; power means for controlling the movements of each said gun turret; a pair of vertically aligned columnar turret supports attached, respectively, above and below said structural support means arranged for the support of said upper and lower gun turrets within said respective openings; said structural support means constructed and arranged in such manner that the opposite side of said fuselage is unobstructed to permit fore and aft access therethrough.

5. A waist gun turret installation for an aircraft fuselage structure having vertically aligned openings in its upper and lower portions, including a pair of longitudinally spaced transverse former rings in the structure of said fuselage disposed on each side of side aligned openings in the longitudinal direction, laterally inwardly extending elements supported from one side only of each of said former rings, longitudinal elements extending between the inner free ends of said laterally extending elements, said laterally extending elements and said longitudinal elements cooperating to form a gun turret platform extending into the central portion of the fuselage from one side of said fuselage structure only, vertically aligned columnar supports attached to said gun turret platform extending above and below said platform, said columnar supports having upper and lower terminal portions each adapted for rotation about both vertical and horizontal axes, gun turret carrying means supported from said upper and lower columnar terminal portions within each of said fuselage openings, and power transmission means housed within said columnar supports for the vertical and horizontal movement of each of said upper and lower gun turrets, said gun turret platform constructed and arranged

to provide a passageway along the opposite side of the interior of said fuselage.

6. In an aircraft gun turret installation, an aircraft fuselage having an opening therein, a part-spherical turret mounted for azimuthal and elevational movements within said fuselage opening, a hollow columnar support member rotatably journaled within said aircraft fuselage on a vertical axis passing through the center of said fuselage opening, a drive shaft co-axially mounted internally within said hollow columnar support member, yoke means pivotally mounted upon a horizontal pivot journaled within said rotatable columnar support member and operatively engaging said drive shaft, worm drive means for rotating said internal drive shaft, a unitary bevel-gear worm drive operatively associated with said drive shaft and said yoke pivot for rotating said yoke means about the horizontal axis of its said pivot, structural means adapted to fixedly support said turret from said rotatable yoke means, further drive means including a worm gear operatively associated with said columnar support member arranged for the rotation of said columnar support member about the first said vertical axis for azimuthal movements of said yoke means and said attached gun turret about said vertical axis, the rotation of said yoke means about said horizontal pivot axis imparting elevational movements to said gun turret.

7. An aircraft gun turret installation within a fuselage having a vertically directed opening through an upper portion thereof, comprising a vertical pedestal support assembly axially disposed with respect to said opening, said pedestal support assembly including a hollow base member fixedly attached to said aircraft fuselage, a hollow rotatable support member coaxially journaled within said fixed base member, a yoke member mounted for rotation about a pivot having a horizontal axis transverse to that of said pedestal support assembly, said yoke member pivot journaled within said rotatable support member, ordnance means housed within a turret fairing fixedly carried by said yoke member, drive means housed within said hollow base member arranged to rotate said yoke member and its attached ordnance means and turret fairing about a vertical axis, a vertical drive shaft coaxially journaled within said hollow rotatable support member, gear means operatively connecting said vertical drive shaft with said yoke member pivot, and further drive means housed within said hollow base member arranged to elevate said yoke member and its attached ordnance means and turret fairing by rotation of said vertical drive shaft and the associated gear means.

8. An aircraft gun turret installation comprising an aircraft fuselage structure, an opening through a wall of said fuselage structure, a pedestal turret support supported upon said fuselage structure having a major axis extending through said fuselage wall opening, said pedestal turret support comprising a fixed base portion, a tubular torque portion journaled in said base portion for rotation about said major axis, a cap portion carried by said tubular torque portion for rotation therewith about said major axis, a yoke portion carried by a pivot journaled within said cap portion for rotation about an axis normal to said major axis, a drive shaft disposed within said tubular torque portion journaled for rotation therein about said major axis, gear means disposed within said cap portion

operatively engaging said drive shaft and said yoke portion pivot, a gun turret carried by said yoke portion and separate drive transmission means journaled and housed within said pedestal support constructed and arranged to rotate said yoke member and attached gun turret in azimuth by rotation of said tubular torque portion and in elevation by rotation of said drive shaft, gear means and said yoke pivot.

9. In an aircraft gun turret, a supporting structure, a tubular base portion fixedly attached to said supporting structure, a tubular column member journaled for rotation within said fixed base portion about a major axis, a pivot element journaled within said column member for rotation on an axis transverse to said major axis, a gun turret supported upon said pivot element, drive means for rotating said tubular column member about said major axis for movement of said gun turret in azimuth, and separate drive means including a worm gear segment fixed to said pivot driven by bevel gearing enclosed by and journaled within said tubular column member for movement of said gun turret in elevation.

10. In a gun turret mounting, a base member fixedly attached to a supporting structure, a tubular member journaled within said base member for rotation therein about a major axis, a cap member carried by said tubular member having a pivot journaled therein for rotation upon an axis transverse to said major axis, a support member fixedly attached to said pivot for the support of a gun and its fairing, worm gear means in operative engagement with said tubular member for its rotation about said major axis and the rotation of said gun and fairing in azimuth, and separate power transmission means including a worm and gear segment extending from within said fixed base portion into said cap portion in operative engagement with said pivot arranged for the rotation of said pivot about its transverse axis and the concurrent elevational movement of said support member and its attached gun and fairing.

11. In an aircraft gun turret installation, a supporting structure, a pedestal member defining a major axis of turret rotation in azimuth, a tubular column member journaled at its first extremity within said pedestal member for rotation about said major axis, said column member having a pivot journaled within its opposite extremity for rotation of said pivot on an axis transverse to said major axis, a yoke member fixedly attached to said transverse pivot, gun means carried by said yoke member, worm gear means for driving said column member and said gun means in azimuth about said major axis, a shaft member journaled within and extending co-axially with said column member, a bevel gear set in meshing engagement with one terminal of said shaft member, a worm element journaled within said column member for rotation with one of the gears of said bevel gear set, a gear segment attached to said transverse pivot in meshing engagement with said worm element, and worm gear means operatively connected to the opposite extremity of said shaft member for rotating said shaft member, said bevel gear set, and said worm and gear segments for movement of said yoke member and the attached gun means in elevation about the axis of said transverse pivot.

12. A columnar type support for an aircraft gun turret comprising a tubular base portion fixedly supported upon the aircraft, a tubular column portion rotatably journaled within said

fixed base portion for rotation about a major axis of the gun turret, pivot means carried by said column portion journaled therein for rotation about an axis normal to said major axis of the gun turret, a gun turret carried by said pivot means arranged for rotation therewith about the axis of said pivot means and with respect to said pivot means about the major axis of said gun turret, power drive means extending through said fixed base portion for the rotation of said column portion and said gun turret about said major axis of rotation for azimuthal movements of said gun turret, and drive transmission means extending from a position within said fixed base portion coaxially through and housed within said rotatable column portion arranged to rotate said pivot means and said gun turret about said pivot axis normal to said major axis for elevational movements of said gun turret.

13. In an aircraft gun turret installation, an aircraft fuselage having an opening therein, a part-spherical turret mounted for azimuthal and elevational movements within said fuselage opening, a hollow columnar support member rotatably journaled within said aircraft fuselage on a vertical axis passing through said fuselage opening, yoke means pivotally carried upon said rotatable columnar support upon a pivot having a horizontal axis arranged for the elevational rotation of said yoke means about said horizontal axis perpendicular to the first said vertical axis of said columnar support, structural means arranged for the fixed support of said turret from said yoke means, drive means including a worm gear fixed to said columnar support member arranged to rotate said columnar support member and the attached yoke means about the first said vertical axis for azimuthal movement of said yoke means and said gun turret, a unitary bevel-gear and worm drive housed within said columnar support member operatively engaging said yoke means for movement of the same about its horizontal pivot axis, a vertical drive shaft co-axially mounted within said columnar support member in operative engagement with said unitary drive for said yoke means, and further drive means including a worm gear engaging said vertical drive shaft constructed and arranged in such manner that said first drive means imparts azimuthal movements to said yoke means and said gun turret by rotation of said columnar support member and said further drive means imparts elevational movements to said yoke means and said gun turret by rotation of said vertical drive shaft and actuation of said unitary bevel-gear and worm drive.

14. A support for an aircraft turret comprising a longitudinally extending fuselage structure

having a vertically directed opening therein, a movable turret disposed within said opening, said fuselage structure including a pair of longitudinally spaced former rings disposed fore and aft of said fuselage opening, transversely extending beams supported from one side only of each of said fuselage rings projecting into the central axial portion of said fuselage structure, structural means for tying together the free end portions of said transversely extending beams, and columnar type support means attached to said transversely extending beams in the region of the central portion of said fuselage for the movable support of said turret constructed and arranged in such manner that the opposite side of said fuselage interior is unobstructed by said aircraft turret installation to permit fore and aft access therethrough.

15. A support for a dual aircraft turret installation comprising a fuselage structure having vertically directed openings therein, upper and lower movable turrets disposed within said openings, said fuselage structure including a pair of longitudinally spaced transverse former rings disposed fore and aft of said fuselage opening, laterally extending beams supported from a first side only of each of said fuselage rings in the region of the mid-height of said fuselage structure, longitudinally extending framing means attached to the unsupported opposite ends of said laterally extending beams, and vertically extending tubular support means attached to the said laterally extending beams for the movable support of said upper and lower turrets within said fuselage openings constructed and arranged in such manner that the opposite or second side of said fuselage structure interior is unobstructed to permit fore and aft access therethrough.

GEORGE BUSSIERE.
